US0D1080212S

(12) United States Design Patent (10) Patent No.: US D1,080,212 S
(45) Date of Patent:  Jun. 24, 2025

(54) CARD STORAGE BOX

(71) Applicant: Gamegenic GmbH, Essen (DE)

(72) Inventors: Alberto Adrian Alonso Perez,
Eggenstein-Leopoldshafen (DE); Sergey
Machin, Duisburg (DE)

() Term: 15 Years

(21) Appl. No.: 29/888,398

(22) Filed: Mar. 30, 2023

Related U.S. Application Data

(62) Division of application No. 35/511,977, filed on Feb. 27, 2021 (U.S. filing date under 35 U.S.C. 384), and having an international filing date of Feb. 27, 2021, now Pat. No. Des. 1,025,601.

(57) CLAIM

The ornamental design for a card storage box, as shown and described.

DESCRIPTION

FIG. 1 is a front view of a card storage box of the present invention;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a top perspective view thereof.

The broken lines depict a boundary of the claim and form no part of the claimed design.

1 Claim, 7 Drawing Sheets
